VALVE

John A. Hastings, Fontneau Road,
South Yarmouth, Mass. 02664

Filed Oct. 24, 1966, Ser. No. 4,410

Term of patent 14 years

U.S. Cl. D23—19
Int. Cl. D23—01

FIG. 1

I claim:

The ornamental design for a valve, as shown.
